UNITED STATES PATENT OFFICE.

CLEMMA R. RANEY, OF CHICAGO, ILLINOIS, ASSIGNOR TO INTERNATIONAL HARVESTER COMPANY, OF CHICAGO, ILLINOIS, A CORPORATION OF NEW JERSEY.

GRAIN SHOCKER.

Application filed June 22, 1923. Serial No. 647,065.

To all whom it may concern:

Be it known that I, CLEMMA R. RANEY, a citizen of the United States, residing at Chicago, in the county of Cook and State 5 of Illinois, have invented certain new and useful Improvements in Grain Shockers, of which the following is a specification:

My invention relates to a grain shocker and more particularly to an improved construction in which the base or butt of the shock is spread in all directions with respect to the body portion of the shock in such a manner that the proper ventilation and airing can be had so as to insure complete curing or drying out of the grain in the bound 10 shock.

One of the objects of the present invention is to provide a simple and efficient butt spreading mechanism which will insure 20 the building of stable shocks in the field.

A further object of the device is to provide a novel construction of butt spreading mechanism which will engage the butt of the shock at points a considerable distance 25 from the plane of the base of the shock when the shock is in its normal prostrate position and swing outwardly and downwardly with respect to the plane of the base of the shock when the shock is set upright on the 30 ground.

A further object of the invention is to provide a novel construction of pivotally mounting the butt spreading mechanism in such a manner that the butt spreading tines 35 move from their normal shock building position, which is the vertical position, to the shock discharging position. In this latter position they assume a diverging or butt spreading position with respect to the shock- 40 ing machine.

These and other objects are attained by providing an improved butt spreading mechanism which co-operates with the shock discharging mechanism to engage the butts 45 of all the sheaves in the shock in a manner to spread the butts of the shock as the shock is being discharged upon the ground by the discharging mechanism.

The invention hereinafter described and 50 claimed is an improvement over the constructions described and claimed in certain other co-pending applications.

In order to disclose my invention I have illustrated the preferred embodiment of the

same as shown in the accompanying drawings. 55

In these drawings Fig. 1 is a top plan view of a shocking machine showing my improved butt spreading mechanism embodied therein; 60

Fig. 2 is a side elevational view of the shocking machine shown in Fig. 1 showing the butt spreading mechanism in its vertical position in full lines and in its butt spreading or horizontal position in dotted 65 lines;

Fig. 3 is a rear elevational view showing the manner in which my improved butt spreading mechanism is mounted on the discharging mechanism of the shocker; 70

Fig. 4 is an enlarged top plan view showing in detail, the manner in which the tines are pivotally connected to the discharging mechanism of the shocker, and

Fig. 5 is an enlarged detail view partly 75 in section showing the latch mechanism for locking the butt spreading mechanism to the shock discharging mechanism.

The shocker shown is of the general type described and claimed in my U. S. Patents 80 Nos. 1,231,195 of June 26, 1917, and 1,292, 922 of February 11, 1919, a rearwardly swinging sheaf delivery member or fork 11' being used, which is carried on a shocker frame 10 and movable by a pitman connection 11 about an axis on a shaft 12 from its sheaf receiving position or the position shown in Fig. 2, wherein it rests beneath the deck of the grain binder, not shown, to its sheaf delivering position, 90 wherein it delivers sheaves in prostrate position in an upwardly and rearwardly movable shock receptacle 13 carried by the rear end of the shocker frame. Also after the manner described in my U. S. Letters Patents Nos. 1,231,195 of June 26, 1917, and 1,242,112 of October 2, 1917, when enough sheaves have been delivered to the shock receptacle 13 to build a shock of a predetermined size, a needle 14 and knotter mechanism 15 are thrown into operation to compress and bind the shock, and at the completion of the compression and binding operation through the rotation of a knotter shaft 16 the shock receptacle 13 is moved 100 upwardly and rearwardly to deposit the shock in an upright position on the ground.

The fork 11' together with all the opera- 105

tive mechanism upon the present shocker are driven from a longitudinally power driven shaft 17, the forward end of which is connected to a second shaft of extensible and flexible character deriving its power from the crank shaft of the grain binder to which the shocker is attached. Both ends of the shaft 17 are journalled in a main frame bearing box 18 which is secured to the main frame by depending ears 19 formed integrally with the bearing box 18 and secured to the main frame by means of bolts.

Also, as described in my Patent No. 1,231,195 of June 26, 1917 in a manner common to all shockers of this type, a continuously operating clutch member 20 is secured to the rear end of the shaft 17 by a pin 21. Engageable with the continuously operating clutch member 20 and adapted to be driven thereby, is an intermittently operated clutch member 22, which is normally controlled by a pawl, not shown. Formed integrally with the intermittently operated clutch member 22 is a drive sprocket 23. Geared to the drive sprocket 23 and operatively driven thereby by means of a driving chain 24 is a sprocket 25 secured to the knotter shaft 16 by a key 26. Through the mechanism just described, it will be understood that the knotter mechanism is operated to bind the shocks through the power derived from the harvester when the number of sheaves in the shock receptacle has reached a predetermined height in said receptacle.

Secured to the rear end of the knotter shaft 16 is a crank 27. The free end of the crank 27 is provided with a stud 28 which has pivotally secured thereto a knuckle joint 40 and pitman connection 29. The lower end of the pitman connection 29 is pivotally secured by a similar knuckle joint 30 journalled on a stud 31 affixed to a crank 32 journalled on the grainward end of a crank shaft 33, which, in turn, is journalled on a supplemental main frame member 10' by means of bearing brackets 34 secured to said frame member. Secured to the grainward end of the crank shaft 33 adjacent the crank 32 is a second crank 35. The crank 35 is adapted to be engaged by a gravity actuated pawl 36 pivoted at 37 to the crank 32. The stubbleward end of the crank shaft 33 is provided with a forwardly extending arm 38 positioned beneath and extending parallel with the shock receptacle 13 when the same is in its normal bundle or sheaf receiving position. The free end of the crank 38 is provided with a roller 39, which is adapted to engage the lower or bottom side of the shock receptacle 13 as the same is actuated about its pivot in the normal operation of setting a shock. Secured to the opposite sides of the rearwardly extending main frame 10 is a transversely extending

pipe or shaft 40. Tiltably mounted by means of hinged brackets 41 on the pipe 40 in a manner to be swung upwardly and rearwardly with respect thereto is the shock receptacle 13.

My improved mechanism for spreading the sheaves in the shock set by the shock receptacle during the setting of the shock and also during the withdrawal of the shocker from the shock after the shock has been set on the ground will next be described.

Securely fixed to the pipe 40 and positioned on the opposite ends thereof, are hinged brackets 42 which are adapted to pivotally support a transversely extending tine shaft 43. The shaft 43 is provided, on its stubbleward end, with a curved portion 44. The upper or free end of this curved portion 44 of the shaft 43 has connected therewith an extension spring 45. The forward end of the extension spring 45 is connected to the main frame 10 of the shocker. The extension spring 45 returns the shaft 43 together with the tines, hereinafter described, to their home or normal vertical position. Positioned on the opposite sides of the medial line of the shocker, and pivoted to the shaft 43 at 46, are two sets of butt spreading tines 47. These tines are of a crank-like construction and comprise a normally vertically extending portion 48, an offset portion 49 and a butt engaging portion 50. The butt engaging portion is angled slightly with respect to the pivoted or vertically extending portion 48, as clearly shown in Fig. 1. Thus, it will be appreciated that when the oppositely disposed sets of tines are in their normal vertical position (Fig. 3) they are disposed in parallel relationship with respect to each other and that when they are in their horizontal or butt spreading position (Fig. 1) they assume a diverging position. In order to strengthen the pivotal connections of the tines 47 with the shaft 43, I have provided spacer brackets 51 secured to the shaft 43 by means of bolts 52. These brackets 52 are provided with apertures 53 in which the upper parts of the vertical portions 48 are pivotally supported. The tines are retained in their pivotal positions on the shaft 43 by cotter pins 54. Each set of tines positioned on the opposite sides of the medial line of the shocker is connected together by a tie bar 55, which in turn, is held against displacement by a second bar 56 pivoted to the tie bar 55 at 57 and pivoted to the bracket 51 at 58. The tines are actuated to swing about their respective pivots by a pitman connection 59. The inner ends of the pitman connection 59 are pivotally connected adjacent the pivots 58 to bars 56. The outer ends of the pitman 59 are pivotally connected to brackets 60 secured to the pipe 40.

From the construction just described, it will be seen that as the shock receptacle 13 is actuated or tilted upwardly and rearwardly in the operation of discharging the shock upon the ground, the butt spreading mechanism, which includes the tines 47, is moved in unison with the receptacle 13 and during such movement the tines 47 are swung about their pivots 46 from their normal vertical and parallel positions shown in Fig. 3 to their horizontal diverging positions as shown in Fig. 1. It will also be noted that when the tines are in their normal or vertical positions they extend forwardly in advance of their pivots and that as the shock receptacle together with the tines are swung to discharge the shock, the tines are then swung rearwardly with respect to their pivots to such an extent that the upper portions 50 of the respective tines assume a position in which a plane extending transversely and through the pivot portions 48 of the tines will almost include these portions 50. (See Figs. 2 and 4.)

The butt spreading mechanism, including the shaft 43 and the tines 47 is normally locked in its vertical position to the shock receptacle 13 by a latch 61 pivoted to the receptacle 13 by means of a pin 62 pivotally connected to the bracket 62' secured to the receptacle 13. The free end of the latch 61 is pressed downwardly by a compression spring 61' in a manner to engage a pawl 63 secured to the shaft 43 by means of clamping bolts 64. The latch is actuated to automatically unlock, by means of a rearwardly projecting portion 63' engaging the underside of the latch 61, the butt spreading mechanism from the receptacle 13 so that the receptacle 13 may return to its normal sheaf receiving position independently of the butt spreading mechanism. The receptacle 13 is returned to its normal sheaf receiving position by means of an extension spring 64 connected at its forward end to the shocker frame and at its rearward end to the receptacle 13 by means of a chain 65. After the shock has been set upon the ground and the tines 47 have been withdrawn from beneath the shock, the extension spring 64, connected between the frame 10 and the curved portion 44 of the shaft 43, returns the tines 47 to their home or vertical position, as shown in Figs. 2 and 3.

In the operation of my improved shock mechanism it will of course, be understood that the shock is built prostrate in the receptacle 13 by means of the sheaf delivery member 11' delivering or conveying the sheaves from the binder deck of the harvester to the sheaf receptacle. When the sheaves in the shock receptacle have reached a predetermined height or bulk, the intermittently operating clutch member 22 is tripped, thus connecting this clutch member 22 with the

continuously operating clutch member 20. Through this mechanism the knotter shaft 16 is driven by the sprockets 23, 25 and chain 24 and the crank 27 is swung upwardly, thereby elevating the crank 32 until the gravity actuated pawl 36 drops by its own weight and engages the second crank 35. Then upon the downward movement of the crank 27, through the pitman connections 29 and the crank 32, the second crank 33 is swung clockwise, swinging the arm 38 with the roller 39 upwardly and rearwardly. This upward and rearward movement of the crank arm 38 is transmitted to the shock receptacle 13, setting the shock in a vertical position and swinging the butt tines 47 from the vertical position shown in Figs. 2 and 3 to the horizontal and diverging position shown in Fig. 1. As these tines are swung from their vertical position to their horizontal position, they are swung laterally with respect to the discharging mechanism in a manner to spread the butts of the shock laterally with respect to the body of the shock, as the shock is being set down upon the ground. It will also be noted that the tines 47 in their vertical position extend forwardly a considerable distance from the plane of the base of the shock and thereby firmly engage the shock in a manner to insure the proper spread of the shock as the same is being set upon the ground. As previously described, the tines are actuated to swing about their respective pivots through the pitman 59 having their outer ends connected to the brackets 60 on the opposite ends of the pipe 40 and their inner ends pivotally connected to the bar 56, which in turn, is pivotally connected to the tie bar 55, and as the tines 47 are actuated with their shaft 43 on the hinges 42 from the vertical position to their horizontal position, the tines are simultaneously actuated to swing about their individual pivots 46 on the shaft 43.

From the construction just described, it will be understood that as the shocker is withdrawn from the shock with the tines extending in diverging positions beneath the shock, and that as these tines are withdrawn in this position they have a tendency to drag or pull the sheaves in a longitudinal direction, thereby longitudinally spreading the butts of the shock as well as laterally spreading the shock during the withdrawal movement of the tines from beneath the shock.

By reason of this construction it will be readily seen that I have provided a very simple and very efficient butt spreading mechanism and one which is adapted to adequately spread the butts of the shock in such a manner as to insure the proper curing and drying out of the grain in the shock.

What I claim as my invention and desire to secure by Letters Patent is:

1. A shocking machine comprising a

frame, a shock discharging mechanism carried thereby, a butt spreading mechanism pivotally mounted on said shock discharging mechanism, and means for actuating said butt spreading mechanism from a position forwardly of its pivot to a position laterally of its pivot.

2. A shocking machine comprising a frame, a shock discharging mechanism carried thereby, a butt spreading mechanism pivotally mounted on said shock discharging mechanism, and means for moving said butt spreading mechanism rearwardly with respect to its pivot as said shock discharging mechanism is actuated to discharge a shock.

3. A shocking machine comprising a frame, a shock discharging mechanism carried thereby, a butt spreading mechanism pivotally mounted on said shock discharging mechanism, and means including a pitman connection connecting said butt spreading mechanism with said frame for moving said butt spreading mechanism rearwardly with respect to its pivot as said shock discharging mechanism is actuated to discharge a shock.

4. A shocking machine comprising a frame, a shock discharging mechanism carried thereby, and butt spreading mechanism mounted on a substantially vertical pivot on said discharging mechanism for spreading the butts of the shocks set by said discharging mechanism.

5. A shocking machine comprising a frame, a shock discharging mechanism carried thereby, and a plurality of substantially vertically pivoted tines mounted on said discharging mechanism for spreading the shock set by said discharging mechanism.

6. A shocking machine comprising a frame, a shock discharging mechanism carried thereby, a plurality of substantially vertically pivoted tines mounted on said discharging mechanism for spreading the butts of the shock set by said discharging mechanism, and means for actuating said tines about their pivots.

7. A shocking machine comprising a frame, a shock discharging mechanism carried thereby, and a plurality of substantially vertically pivoted tines mounted on said discharging mechanism for spreading the shock set by said discharging mechanism, said tines being normally positioned forwardly of their pivots and adapted to swing laterally with respect thereto.

8. A shocking machine, comprising a frame, a shock discharging mechanism mounted on said frame, a plurality of butt

spreading tines normally extending vertically through the butts of the shock in said shocking machine, said tines being pivotally mounted on said discharging mechanism and having their pivots extending substantially parallel with the portions of the tines extending through the butts of the shock, and means for actuating said tines about their pivots.

9. A shocking machine comprising a frame, a shock discharging mechanism mounted on said frame, a plurality of butt spreading tines normally extending vertically through the butts of the shock in said shocking machine, said tines being pivotally mounted on said discharging mechanism and having their pivots extending substantially parallel with the portions of the tines extending through the butts of the shock, and means including a pitman connection connecting said tines with said frame for actuating said tines about their pivots.

10. A shocking machine comprising a frame, a shock discharging mechanism carried thereby, a plurality of butt spreading tines normally extending substantially in a vertical plane and pivotally mounted on said discharging mechanism, and means for moving the upper portion of all of said tines rearwardly in a plane with respect to their pivots as said discharging mechanism is actuated to discharge a shock.

11. A shocking machine comprising a frame, a shock discharging mechanism carried thereby, butt spreading mechanism mounted on said discharging mechanism, said butt spreading mechanism including a transversely extending shaft journaled on said shock discharging mechanism, a plurality of tines extending through said shaft and pivotally mounted therein, and means for actuating said tines about their pivots as said shock discharging mechanism deposits a shock upon the ground.

12. A shocking machine comprising a frame, a shock discharging mechanism carried thereby, butt spreading mechanism mounted on said discharging mechanism, said butt spreading mechanism including a transversely extending shaft journaled on said shock discharging mechanism, a plurality of tines extending through said shaft and pivotally mounted therein, and a pitman connection connecting said tines with said frame.

In testimony whereof I have signed my name to this specification on this 18th day of June A. D. 1923.

CLEMMA R. RANEY.
